(57) **CLAIM**

The ornamental design for a plumbing fixture, as shown and described.

DESCRIPTION

In a preferred embodiment, the nature of this product is as a plumbing fixture in the form of a bathing tub, primary useful for washing the human body.

FIG. 1 is a left, top, front perspective view of a plumbing fixture embodying my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a top plan view of a plumbing fixture according to another embodiment of my new design, the left side and right side elevational views thereof being identical to FIGS. 4 and 5, respectively;

FIG. 9 is a front elevational view thereof;

FIG. 10 is a left, top, front perspective view of a plumbing fixture according to another embodiment of my new design;

FIG. 11 is a top plan view thereof;

FIG. 12 is a side elevational view thereof;

FIG. 13 is a left side elevational view thereof;

FIG. 14 is a right side elevational view thereof;

FIG. 15 is a bottom plan view thereof;

FIG. 16 is a top plan view according to another embodiment of our new design, the left side and right side elevational views thereof being identical to FIGS. 13 and 14, respectively; and,

FIG. 17 is a front elevational view thereof.

The broken line representations of wall and apron structure in FIGS. 1-9, a drain in FIGS. 2-9 and 11-17, and an overflow in FIGS. 1, 2, 5, 7, 8, 10, 11, 14, 15 and 16, are for the purpose of illustration only, and form no part of the claimed design.
